(57) **CLAIM**

The ornamental design for a shroud for a modular sensor system as shown and described.

DESCRIPTION

FIG. 1 is a perspective view of a shroud for a modular sensor system showing our new design, wherein the broken lines showing the exemplary sensors is for the purpose of illustrating environmental structure and form no part of the claimed design;

FIG. 2 is the perspective view shown in FIG. 1 with the exemplary sensors removed;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The remaining portions of the drawings shown in broken lines define the bounds of the claimed design and form no part of the claimed design.
